UNITED STATES PATENT OFFICE

2,443,755

DEMOUNTABLE SANDING DISK

Martin Vass, River Rouge, Mich.

Application December 9, 1946, Serial No. 715,074

2 Claims. (Cl. 51—197)

1

This invention relates to a special sanding disc applicable to plane surface finishing work.

The object of my invention is to provide a surface sanding disc, constructed for receiving and retaining interchangeable surface sheets of abrasive material thereon, without cementing or gluing same, as is ordinarily required with the sanding units now in common use.

Another object is to provide a demountable sanding disc that can readily be mounted on any power drive shaft end, applicable to either solid or flexible shaft units.

A further object is to produce a sanding disc structure applicable to large sanding units, designed to withstand eccentrically applied working pressure, without affecting its operation.

A still further object is to provide an interchangeable abrasive sheet sanding disc that is simple in construction, easily and efficiently operated and that can be manufactured at a very low cost.

These several objects are attained in the preferred form by the construction and arrangement of parts more fully hereinafter set forth.

Similar parts on all drawings are marked by similar numerals or letters.

Fig. 1 is a back view of my demountable sanding disc showing the general construction and arrangement of the clamping frame, and the shaft mounting head attached thereto.

Fig. 2 is a top view of the assembled sanding unit, showing the relative position of the various operating parts.

Fig. 3 is another back view of the disc with the clamping frame and bearing mounting unit removed, as on the line 3—3 of the Fig. 2, showing the means of folding and clamping the interchangeable abrasive sheets to the mounting disc section.

Fig. 4 is a cross-sectional view taken on the line 4—4 of the Fig. 1, showing the assembled section construction.

Fig. 5 is a top view of the assembled sanding disc showing the disc abrasive surface.

Fig. 6 is an edge view of the modified bearing unit for mounting the assembled disc on a power drive shaft end.

In general, my demountable sanding disc comprises a double disc assembly united by a rigid shaft mounting head, and provided with a resilient member beneath the attached abrasive sheet surface, the sheet being retained thereon by special clamping means.

I will now describe more fully the detailed

2

construction of my device, referring to the drawings and the marks thereon.

The mounting disc 1 is made a thin, circular section of predetermined diameter and thickness, preferably of wood, or plywood, or some suitable light metal, turned to a true circular circumference and corresponding faces, and provided with a center bearing recess *a* therethrough, positioned concentric with the disc circumference. Adjacent the mounting disc 1, on the back side thereof, is mounted a clamp frame disc 2, preferably made of the same material and of the same diameter, but preferably formed with radially positioned spoke sections *b*, and likewise provided with a central bearing recess *c* therethrough, positioned concentric with the disc circumference and the adjacent mounting disc recess *a*. The two discs 1 and 2 are slightly separated by a thin sheet filler 3 interposed therebetween, centrally located and symmetrically positioned about the common disc axis. A series of countersunk clamping screws 4 are mounted around the disc edges, positioned symmetrically about the disc centers, designed for firmly clamping the adjoining disc rims tightly together. On the back side of the clamp disc 2 is fixedly mounted a metal power shaft driving head 5, centrally located thereon. The driving head 5 is preferably formed of a thin rectangular metal plate *d* having a tubular drive shaft bearing *e* projected from one side thereof and a threaded bearing spindle *f* projected from the opposite plate side, both units being positioned concentric with the disc axis of rotation. The driving head plate *d* is connected to the discs 1 and 2 by the radially positioned clamp bolts 6 as shown in the Fig. 4 of the drawings, and reacts as a stiffening collar for the assembled disc section for the larger sized units. However, the clamp bolts 6 may be extended through the clamp disc 2 walls only, if desired, greatly facilitating the interchanging of the abrasive sheets on smaller sized sanding discs. The thin sheet filler 3 is preferably of a size to include the bearing clamp screws 6 should they be mounted through both disc sections. The tubular shaft bearing section *e* is made of a size to receive and fit the end of the power drive shaft with which the sanding disc is to be used, and is provided with a suitable set screw 7 for securely attaching the disc assembly thereon. If desired, or required by the special driving shaft end, the tubular bearing section *e* may be internally threaded, as an attaching means. Further, in cases where full abrasion surface is required, the bearing spindle *f* may be shortened to extend

only part way through the assembled disc sections. Over the inside face of the mounting disc 1 is placed a thin circular pressure pad 8 of the same diameter as the disc, of some suitable resilient material, such as rubber, fabric, or any other suitable resilient material. The resilient pad 8 is preferably cemented to the disc surface for convenience in replacement of the surface abrasive sheet 9 which is mounted over the resilient pad 8 surface. The abrasive sheet 9 preferably of sandpaper, emery cloth, or similar material, is made of a diameter slightly greater than the mounting disc, and is formed with projected notched edges g around the entire circumference thereof, all foldable over the pad 8 and mounting disc 1 edges, the notched edges g being projected between the mounting disc and clamp disc edges, and securely clamped therebetween by the clamp bolts 4, uniting the sections into a rigid abrasive disc assembly, ready for use. The abrasive sheet discs 9 are interchangeable at will, and may readily be removed by releasing the clamp screws 4 and 6, and a new sheet may then be inserted therein. The resilient pad 8 allows slight contact variations as may appear on the work surfaces, without causing wheel vibrations of the rotating sanding disc.

The threaded spindle 7 may be extended through the disc assembly and provided with an external collar washer 10 and clamp nut 11, as shown in the Figs. 2 and 4, where the disc is to be used on a stationary machine frame, but applicable to work surfaces on the upper disc half only, and a fixed pivot bearing 12 mounted in the pivot socket 13 of the spindle end, as indicated in the Fig. 4, or the spindle may be foreshortened and provided with a countersunk collar 13 and clamp screw 14 as indicated in the Fig. 6 of the drawings. The application and operation are the same in either case.

Having fully described my demountable sanding disc what I claim as my invention and desire to secure by Letters Patent is:

1. A demountable sanding disc adapted for finishing plain work surfaces, and used with a power drive shaft, comprising a circular mounting disc of predetermined diameter, and a circular clamp disc of the corresponding size, positioned adjacent to and concentric with each other, suitable disc clamping bolts mounted around rim sections for tightly clamping them together, a

resilient surface disc pad mounted over the outer face of said mounting disc, a circular sheet of suitable abrasive material of larger diameter, mounted over said resilient pad disc with the extended sheet edges notched and folded over the mounting disc edges and projected between the adjoining disc edges and tightly clamped therein by the disc clamping bolts, and a suitable shaft head unit mounted on the opposite side of said clamp disc, positioned concentric with the assembled disc axis of rotation, designed for mounting said sanding disc on the end of a suitable driving shaft section.

2. A demountable sanding disc adapted for finishing plain work surfaces, and used with a suitable driving shaft, comprising a circular mounting disc and a circular clamp disc of a predetermined size, positioned adjacent to and concentric with each other, a thin sheet filler centrally positioned between the respective disc centers, suitable clamping bolts mounted around the disc rims for tightly clamping said discs together, a resilient disc pad mounted over the outer surface of said mounting disc and attached thereto, an enlarged circular sheet of abrasive material mounted over the resilient pad surface, designed and positioned with the extended sheet edges notched and folded over and between the respective mounting disc and clamp disc edges, and tightly clamped therebetween by the disc rim clamping bolts, a suitable shaft head mounted on the opposite side of said clamp disc, positioned thereon concentric with the disc axis of rotation, designed for mounting over the end of a power drive shaft and provided with an extended disc pivot projected from the opposite side thereof, and means for securely attaching said shaft head to a driving shaft.
